UNITED STATES PATENT OFFICE

WILLIAM A. SPRING, OF THOMPSONVILLE, CONNECTICUT, ASSIGNOR TO BIGELOW
SANFORD CARPET CO., INC., A CORPORATION OF MASSACHUSETTS

DESIGN FOR A CARPET

Application filed March 15, 1933. Serial No. 47,457. Term of patent 7 years.

To all whom it may concern:

Be it known that I, WILLIAM A. SPRING, a citizen of the United States, and resident of Thompsonville, in Hartford County, and State of Connecticut, have invented a new, original, and ornamental Design for a Carpet, of which the following is a specification, reference being had to the accompanying drawing, forming part thereof, in which a plan view of the carpet is shown.

The dot and dash lines define the unit of

the design. The lower right hand corner of the unit designated "C" is repeated at the angle designated "D", mid-way the left-hand vertical edge, while the lower left hand corner of the unit designated "B", is repeated at the angle designated "A", mid-way the right-hand vertical edge.

I claim:

The ornamental design for a carpet substantially as shown and described.

WILLIAM A. SPRING.
